UNITED STATES PATENT OFFICE.

DANIEL WATTS TROY, OF NEW YORK, N. Y.

METHOD OF SELECTING ELECTRICAL IMPULSES.

SPECIFICATION forming part of Letters Patent No. 755,586, dated March 22, 1904.

Application filed July 11, 1903. Serial No. 165,152. (No model.)

To all whom it may concern:

Be it known that I, DANIEL WATTS TROY, a citizen of the United States of America, residing in the city, county, and State of New York, (having a post-office address at 32 Broadway, in said city,) have invented certain new and useful Improvements in the Method of Selecting Electrical Impulses, of which the following is a specification, reference being had to the accompanying drawings, forming a part hereof.

My invention relates to the selection of electrical impulses according to their frequency, selection being understood to mean the operation of receptive apparatus by impulses of a certain frequency or frequencies and the non-operation of such apparatus by impulses of other or "foreign" frequencies. The method contemplates, in effect, both selection and non-interference, if the two can be considered as separable.

The object of my invention is to provide an efficient and reliable method for securing such selection for use in multiplex telegraphy over wires, selective telephony on party-lines, wireless or space telegraphy, and the wireless control of apparatus at a distance, such as torpedoes, or, in fact, any apparatus desired to be controlled by electrical impulses; and the object, is further, to obtain such selection for any purposes where desirable.

In the drawings, Figure 1 is one form of receiving instrument; Fig. 2, another form; Fig. 3, still another. Fig. 4 is a detail of a modification of Fig. 1, and Fig. 5 is an electrostatic application of the method.

I am familiar with the method of electrically tuning receiving-conductors used in wireless telegraphy; but my system has nothing in common with such method, except that it may be used to advantage therewith. I am also familiar with the methods used by Professor Fessenden, in which currents produced in receiving-conductors are divided by phase-splitting means related to the frequency of the transmitter from which it is desired to select and in which an operative phase difference of one hundred and eighty degrees is used in the instruments; and I am also familiar with his system of transmitting simul-

taneously out-of-phase waves and receiving them by tuned receivers and with his system of receiving by "beats" produced by two transmitted sets of waves of different periodicity. In my system, however, there is a distinct and radical difference from those above named in that my receiving instruments are not merely most responsive when energized by waves of the frequency desired to be selected, but are only responsive when energized by waves of such frequency or, as extreme delicacy might be required to select to the exact frequency, are responsive only to a closely-related range of frequencies—say frequency N and a few frequencies below and above N or approximately frequency N.

In my method I split the phase of currents produced by the waves in receiving-conductors or split the phase of alternating currents, as the case may be, and then operate by such out-of-phase currents so produced receptive apparatus operative only within a given frequency range, approximately frequency N. With the device shown in Fig. 3 the selection is practically to frequency N.

Generally the method contemplates a receiving instrument operative only at a given phase displacement in the energizing-currents, and this condition is realized by causing a brake effect upon biphasic apparatus by a portion of the received energy, except at the maximum efficiency of the receptive apparatus, when the brake is overcome.

Referring to the drawings, Fig. 1 shows a receiver in the form of a rotary field-motor, 11 being a pair of field-coils and 22 being a second pair at right angles to the first pair. 10 is the armature or rotor embraced by such coils, (though it is obvious that either rotor or field-coils may be the movable member.) Said field-coils are supplied, respectively, in shunt relation from a receiving-conductor 5 through phase-displacing means in one branch 7 (an inductance) and through another phase-displacing means 8 (a condenser) in the other branch. 7 and 8 are so related as to cause a difference of phase in the currents in the two pairs of field-coils of ninety degrees at frequency N. It is obvious that without further modification such a receiver would re-

Corrections in Letters Patent

spond in degree to any reasonable frequency. To render the instrument inoperative at foreign frequencies, an electromagnetic brake is provided, consisting of a pair of approximated flat coils 9 and 9', one of which is rigidly connected to the movable member of the motor and the other fixed on the base of the instrument or otherwise. Either the whole or a part of the received energy is directed through such brake-coils in series or in parallel, and such coils are so proportioned, adjusted, or related to the power factor of the motor as to normally overpower it except at the maximum power for unit current of such motor. A local circuit 11 12 13, embracing indicating mechanism as a sounder, is adapted to be made operative whenever the motor overpowers the brake. In such a motor the maximum torque (practically the standstill torque) per unit current will be when the condition of a circular magnetic field is reached—viz., at a phase-angle of displacement equal to the coil-angle, or ninety degrees in both. In the further discussion it may be assumed that unit current is being transmitted through the coils and that means, such as resistance and the like, are provided to render the energizing-currents equal or their effects equal when out of phase the proper amount. It is obvious that a greater or less coil-angle would require a corresponding phase-angle for the condition of maximum efficiency, and in the case where several such motors were operated at one station one set of phase-displacing means might be used to supply several motors. It is obvious, further, that other means of producing an operative phase difference might be used, and it is evident that any known means—such as microphonic contacts, mirrors, or other devices—may be used to advantage to indicate motion of the rotor or movable member of such motor instead of the means shown in Fig. 1. It is possible as a variation of this method that two such motors be placed in opposition, the power factor of the one varying practically with that of the other, except at and near the maximum of one, when the one having the higher maximum would overpower the other.

In Fig. 2 two brake or in-phase coils 15 15' are shown similar to 9 9' and are opposed by two out-of-phase coils 16 16'. Such out-of-phase coils are energized as follows: By a proper capacity 17 a lead of forty-five degrees is produced in 16 over the received current, while a lag of forty-five degrees is produced in the other branch of the split, as before, by inductance 17', (frequency N being assumed.) 16, however, is not energized directly from the lagging branch, but by a transformer 18, having its primary energized by such lagging current. As the current in the secondary of the transformer would be lagging behind that of the primary by, say, ninety degrees, a total lag of one hundred and thirty-five degrees

could be produced at frequency N in the lagging out-of-phase coil. The figures given would not be the best possible in practice; but the method is essentially the same whatever operative phase differences are produced in the primary branches of the phase split. In practice the inductive effect of the lagging out-of-phase coil would require a different proportion in the phase-displacing means from the figures named. If now the coils 16 and 16' be energized by currents one hundred and eighty degrees out of phase, produced as above described, and they are oppositely wound, as contemplated, they will have similar directional currents and will mutually attract, and if given a mechanical advantage over the in-phase or brake coils at such stage will cause movement of the light lever 20, supporting coils 15 and 16. At all other frequencies the in-phase coils will prevent such motion and hold the lever down against the stop 22, (shown to the left of the fulcrum 21.) Movement of the lever can be indicated by a mirror 23 or otherwise. It is obvious that only at one frequency will the coils 16 and 16' have their maximum efficiency, and it is possible by such means to select within a very narrow range of frequencies related to the maximum effect of the out-of-phase coils.

In Fig. 3, 34 is a reed of fixed rate N . 35 95 is a coil fixed on the free end of such reed. 35' is a similar coil on the base of the instrument. 35 and 35' are supplied, respectively, with currents differing in phase ninety degrees at frequency N^2 , the means being the same hereinbefore described and related to the frequency N^2 desired to be selected. It is obvious that coils 35 and 35' will twice mutually attract and twice mutually repel during each cycle of the current at frequency N^2 , and such attractions and repulsions will be equally timed and alternated at such frequency. Should the frequency be lower than N^2 , there will not be a quarter-phase displacement, and consequently such operative impulses will not be equally timed, nor will the impulses be timed with the rate of the reed and the apparatus will be inoperative. A higher frequency than N^2 will also be inoperative for the same reasons. Instead of coils 35 and 35'—conducting-disks 115 may be used instead and the electrostatic attractions and repulsions used instead of the electromagnetic effects. Combined with an electric tuning system this method of operating a vibratory receiver insures a threefold 120 safeguard against foreign rates.

Fig. 5 shows an electrostatic modification of Fig. 2, in which conducting-disks 40 and 40' are normally overpowered by other similar disks 41 and 41', the last pair energized by 125 means similar to those shown in Fig. 2. 45 is a light lever supporting the upper disks upon a fulcrum 46. The operation is analogous to that of Fig. 2 and needs no explanation. 130

Fig. 4 shows a microphonic contact 50, consisting of a cam on the axis of the rotor 10 and bearing on a carbon block 53. By this means variations of local currents may be utilized to indicate motion of the rotor. The microphonic method of indicating operative movement may of course be applied to others of the types of instruments shown herein.

Variations of the electromotive force, on account of the utilization of a part of the received energy to operate the brake, will not prevent the selective action, as stronger impulses produce related brake effects. It is obvious that "reed" as herein used does not necessarily mean a fixed vibratory member, as the same operative effect can be obtained with apparatus controlled in any manner so as to produce a fixed mechanical rate of vibration.

So far as I am aware split-phase current impulses have not been used to any extent in ordinary telegraphy over wire circuits or in selective telephony, and as far as I am advised the only use of split-phase devices in wireless or space telegraphy is where apparatus is made thereby more sensitive to a certain frequency of waves, though not in any sense sensitive only to a given frequency as I contemplate. It should be noted that an instrument "operative only by electrical impulses of given frequency" is an instrument inoperative by impulses of other frequencies and not merely operative to less extent by the foreign frequencies.

I do not confine myself in my method of selection to cases where the "out-of-phase-ness" of currents is the governing feature by producing greatest power at such a phase difference as may be desired, for it is obvious that apparatus of a differential nature might be constructed where the out-of-phase-ness would be manifest as a reactance merely and not operate to produce a rotating magnetic field or to produce the timed intervals necessary in my reed-controlled instruments.

In the claims following I mean by "electrical impulses" all kinds of electromagnetic or electrical waves capable of producing currents in receiving-conductors.

With very high frequencies it is obvious that it would be impracticable to use motor-coils in the receivers with high self-inductive coefficients, for at such very high frequencies the energy would be choked out of the currents by coils of many turns. At lower frequencies, however, such as in some of the applications noted herein, there need not necessarily be a destructive reactance in the coils, as shown. It is of course intended in all cases that the phase-lagging coil be proportioned to the frequency desired to be selected and might and could in extreme cases take the form of a single turn. The reactance of this coil would be only such as to cause the desired phase displacement and would not choke out energy or render the

current wattless beyond the extent inseparable from the production of the lag. It is obvious that magnetic reactance would not hurtfully affect the energy in the electrostatic types shown herein.

It is obvious, of course, in view of the well-known phenomena of alternating or wave-like currents of electricity, that phase differences can be produced in a variety of ways not particularly pointed out herein.

Having described my invention, what I claim is—

1. The method of selection herein set forth, consisting in causing a phase difference between currents produced by electromagnetic waves in receiving-conductors by means at the receiving-station related to and capable of causing a given phase difference at the frequency of the waves desired to be selected, and energizing by the phase-differing currents so produced responsive apparatus operative only at substantially such given phase difference.

2. The method of selecting electrical impulses herein set forth consisting in causing a phase difference between currents produced by such impulses in receiving-conductors by means at the receiving-station related to and capable of causing such phase difference of given degree at the frequency of the impulses desired to be selected, and energizing by such phase-differing currents so produced responsive apparatus operative only at a phase difference of approximately such given degree, substantially as set forth.

3. The method of selecting electrical impulses herein set forth, consisting in causing a phase difference between currents produced by such impulses in receiving-conductors by means at the receiving-station related to and capable of causing at the frequency of the impulses it is desired to select a given phase difference, and directing such out-of-phase currents so produced respectively in shunt relation through independent windings of apparatus operative only at approximately such phase difference between currents in said windings, substantially as set forth.

4. The method of selecting electrical impulses herein set forth, consisting in causing a phase difference between currents produced in receiving-conductors by such impulses by means at the receiving-station related to and capable of producing at the frequency of the impulses desired to select a given phase difference, and by directing such phase-differing currents so produced through independent windings of biphasic responsive apparatus producing a mechanical force varying with a factor of the phase difference of such currents, and energizing by currents produced by said impulses a brake operative against said apparatus except approximately at the maximum mechanical force of such apparatus, substantially as set forth.

5. The method of selection herein set forth, consisting in causing a phase difference between currents produced in receiving-conductors by electrical impulses by means at the 5 receiving-station related to and capable of producing a given phase difference at the frequency of the impulses it is desired to select, and by directing such phase-differing currents so produced respectively in shunt relation through independent windings of biphasic responsive apparatus, producing a mechanical force passing through a maximum at a given phase difference between currents in said windings, and energizing by currents produced by such impulses a stop device operative against said responsive apparatus except at approximately such maximum, substantially as set forth.
6. The method of selecting electrical impulses consisting in causing a phase difference in currents produced in receiving-conductors by means at the receiving-station related to and capable of producing at the frequency of the impulses which it is desired to select a 20 given phase difference, and by energizing by such out-of-phase currents so produced biphasic responsive apparatus, producing a mechanical force passing through a maximum at a certain phase difference between such phase-differing currents so produced, and energizing by means of currents produced by such impulses a stop mechanism operative against said responsive apparatus except at approximately such maximum, substantially as set 25 forth.
7. The method of selecting electrical impulses herein set forth consisting in receiving such impulses by conductors electrically tuned to the frequency of the transmitter from which 30 it is desired to select, causing a phase difference in currents produced in receiving-conductors by such impulses by means at the receiving-station related to and capable of producing at the frequency of the transmitter from which it is desired to select a given phase difference in such currents, and, by energizing biphasic responsive apparatus with 35 such out-of-phase currents so produced, producing a mechanical force varying with a factor of the phase difference of such currents and passing a maximum at the phase difference corresponding to the frequency of such transmitter, and energizing by currents produced by such impulses a stop mechanism operative against such responsive apparatus except at approximately such maximum, substantially as set forth.
8. The method of selecting electrical impulses herein set forth consisting in receiving 40 such impulses by electrically-tuned conductors, producing a phase difference between currents produced by such impulses in such conductors by means at the receiving-station related to and capable of causing such phase

difference of given degree at the frequency of 65 the impulses desired to be selected, and energizing by such phase-differing currents so produced responsive apparatus operative only at a phase difference of approximately such given degree substantially as set forth.

9. The method of selecting electrical impulses, received by electrically-tuned conductors at the receiving-station, and energizing current-operative biphasic-responsive apparatus, consisting in producing by means of currents produced by such impulses a stop effect on such responsive apparatus except at approximately a given frequency, substantially as set forth.

10. The method of selecting electrical currents of wave character consisting in energizing by such currents in shunt relation responsive apparatus of biphasic character, and, by phase-displacing means related to the frequency of the current desired to select, producing a mechanical force in such apparatus varying with a factor of phase difference between its windings, and energizing by such currents a stop mechanism operative against such apparatus except at approximately such maximum, substantially as set forth.

11. The method of selecting alternating, pulsatory or oscillatory currents consisting in splitting the phase of such currents at the receiving-station by means related to the frequency of the current desired to be selected and directing the phase-differing currents so produced in shunt relation through independent windings of a motor operative only when such currents have approximately a given 90 phase difference, substantially as set forth.

12. The method of selecting herein set forth consisting in directing alternating currents by independent paths in shunt relation through separate windings of biphasic-current-responsive apparatus operative only at substantially a given phase difference between the currents in its windings and producing an operative phase difference in said windings by means related to the frequency of the current to be selected, substantially as set forth.

13. The method herein set forth consisting in directing wave-produced currents by separate paths in shunt relation through independent windings of biphasic-current-responsive apparatus operative only at approximately a given phase difference in such windings and producing an operative phase difference by means related to the frequency of the waves desired to be selected, substantially as set forth.

14. The method herein set forth consisting in splitting the phase of wave-produced currents by means at the receiving-station related to and capable of causing a given degree of phase difference at the frequency of the waves desired to be selected, and energizing by the components of such split-phase currents appa-

ratus of biphasé character operative only at approximately such given degree of phase difference, substantially as set forth.

15. The method herein set forth, consisting in splitting the phase of wave-produced currents by means related to the frequency of the waves desired to be selected, energizing by the components of such split apparatus of biphasé character and preventing by current-operated brake mechanism any movement of such apparatus except at a certain phase difference in such components, substantially as set forth.

16. The method of selecting electrical waves herein set forth consisting in splitting the phase of wave-produced currents at the receiving-station by means capable of producing a given degree of phase difference at a given frequency, and energizing by the resulting phase-differing components responsive apparatus operative only at a phase difference of substantially such given degree, substantially as set forth.

17. The method herein set forth, consisting in dividing the energy of received electromagnetic waves, producing by a portion of such energy a force varying with a function of the frequency and producing by the other portion of such energy an oppositely-acting force less than the first only at substantially a given frequency of such waves, substantially as set forth.

18. The method of selection of electric waves herein set forth, consisting in producing by a portion of the energy of such waves a force varying with a function of their frequency and producing by another portion of the energy of such waves another and oppositely-acting force less than the first only at approximately a given frequency of such waves, substantially as set forth.

19. The method of selection herein set forth consisting in energizing a rotary field-motor by split-phase components of wave-produced currents and preventing the operation of such motor except at its maximum efficiency by a brake operated by wave-produced currents substantially as set forth.

20. The method herein set forth consisting in splitting the phase of wave-produced currents at the receiving-station by means capable of producing a phase difference of given degree at a given frequency, and energizing by the components so produced apparatus operative at a phase difference between such components of substantially such given degree, substantially as set forth.

21. The method herein set forth consisting in opposing forces produced by wave-produced currents and by means at the receiving-station related to the frequency of the waves desired to be selected causing an operative difference in such forces only at approximately such frequency, substantially as set forth.

22. The method herein set forth consisting in opposing forces produced by wave-produced currents and by means at the receiving-station related to the frequency of the waves desired to be selected causing an operative difference in such forces only at substantially such frequency, substantially as set forth.

23. The method of selection herein set forth consisting in producing by a portion of the energy of electromagnetic waves a force varying with a function of the frequency and producing by the remaining portion of such energy an opposing force less than the first only at substantially a given frequency, substantially as set forth.

24. The method herein set forth, consisting in receiving electrical impulses by electrically-tuned conductors at the receiving-station, opposing forces produced by currents caused by such impulses, and, by means related to the frequency of the waves desired to be selected, causing an operative difference between such forces only at substantially such frequency, substantially as set forth.

25. The method herein set forth consisting in combining selection by electrical syntony with selection by opposing forces produced by wave-produced currents, and by means related to a given frequency causing an operative difference between such forces only at substantially such frequency, substantially as set forth.

26. The method of selection herein set forth consisting in producing from a portion of the divided energy of electric waves a force having a maximum at substantially a given frequency, and from the other portion of such energy another force less than the first at such maximum, substantially as set forth.

27. The method of selection herein set forth consisting in dividing the energy of received electrical impulses and normally nullifying the action of the one portion of such energy by the other portion except at substantially a given frequency of the received impulses, substantially as set forth.

28. The method of selection herein set forth consisting in dividing the energy of received electrical impulses and by means related to a given frequency producing an operative excess in one of the portions of such energy over the other only at substantially such given frequency, substantially as set forth.

29. The method herein set forth consisting in dividing the energy of received electrical impulses and utilizing one portion of such energy to normally nullify the action of the remaining portion except at substantially a given frequency, substantially as set forth.

30. The method herein set forth consisting in producing by means related to the frequency of the impulses desired to be selected a phase difference between components of the received impulses and energizing by such components apparatus operative only at sub-

stantially a given phase difference between such components, substantially as set forth.

31. The method herein set forth consisting in splitting the phase of received electrical impulses by means related to the frequency of the impulses desired to be selected and energizing by the phase-differing components so produced apparatus responsive only at substantially a given phase difference between such components, substantially as set forth.

32. The method herein set forth consisting in receiving electrical impulses by conductors electrically tuned to the transmitter, and opposing forces produced by such impulses, and, by means related to a given frequency, causing an operative difference between such forces only at substantially such frequency, substantially as set forth.

33. The method herein set forth consisting in receiving electromagnetic waves by conductors electrically tuned to a given frequency and utilizing a portion of the energy of received electrical impulses to normally nullify the action of the remaining portion of such energy except at substantially such given frequency, substantially as set forth.

34. The method herein set forth consisting in dividing the energy of syntonically-received electrical impulses and producing by one portion of such energy a force varying with a function of the frequency, and having a maximum at a given frequency, and producing from the remaining portion of such energy a force less than the first only at substantially such given frequency of said impulses, substantially as set forth.

35. The method herein set forth consisting in energizing a rotary field-motor by split-phase components of an alternating current and preventing the operation of such motor except at its maximum efficiency by a brake operated by such current, substantially as set forth.

36. The method herein set forth, consisting in dividing the energy of received electromagnetic waves and opposing one portion of such energy against the other, and, by means related to a given frequency, producing an operative difference only at substantially such frequency of such waves, substantially as set forth.

37. The method herein set forth consisting in mutually opposing portions of the energy of received electromagnetic waves and by means related to a given frequency of such waves producing an operative difference only at substantially such given frequency, substantially as set forth.

38. The method herein set forth, consisting in receiving electromagnetic waves by syntonically-tuned conductors; mutually opposing portions of the received energy, and, by means at the receiving-station, producing an operative difference between such portions of such energy only at approximately a given

frequency of such waves, substantially as set forth.

39. The method of selection herein set forth, consisting in causing one portion of the received energy of electrical impulses to nullify the action of the remaining portion except at substantially a given frequency of such impulses, substantially as set forth.

40. The method herein set forth consisting in causing one portion of the received energy of electrical impulses to act against the remaining portion of such energy and so produce an inoperative power factor from the received energy except at substantially a given frequency of such impulses, substantially as set forth.

41. The method herein set forth, consisting in combining with selection by electrical resonance selection by causing one portion of the received energy of electrical impulses to normally nullify the action of the remaining portion of such energy except at substantially a given frequency of such impulses, substantially as set forth.

42. The method herein set forth consisting in mutually opposing portions of the energy of syntonically-received electromagnetic waves, and by means related to a given frequency, producing an operative difference between such portions only at substantially such given frequency, substantially as set forth.

43. The method herein set forth consisting in combining selection by electrical syntony with selection by causing one portion of the energy of received electrical impulses to nullify the action of the remaining portion of such energy except when such received impulses have approximately a given frequency, substantially as set forth.

44. The method herein set forth, consisting in causing a phase difference between components of received impulses and energizing by such phase-differing components apparatus operative only at substantially a given frequency, substantially as set forth.

45. The method herein set forth, consisting in modifying by reactances the power factor of components of received impulses and energizing by such modified components a responsive device operative only at substantially a given frequency of such impulses, substantially as set forth.

46. The method herein set forth, consisting in modifying by respective reactances the power factor of components of received impulses and energizing by such respectively modified components responsive apparatus operative only at substantially a given frequency of such impulses, substantially as set forth.

47. The method herein set forth, consisting in dividing the received energy of electrical impulses and modifying the power factors of the components of the division, and energizing by such modified components apparatus

operative only at substantially a given modification of such components, substantially as set forth.

48. The method herein set forth, consisting in causing phase differences between components of received impulses and energizing by such phase-differing components apparatus responsive only at substantially a given phase difference between such components, substantially as set forth.

49. The method herein set forth, consisting in causing, by means related to a given frequency, a phase difference between components of received impulses, and energizing by such phase-differing components apparatus responsive only at substantially such given frequency, substantially as set forth.

50. The method herein set forth, consisting in causing, by means related to a given frequency, modifications in the power factor of divided components of received impulses, and energizing by such divided components apparatus operative only at substantially such given frequency, substantially as set forth.

51. The method herein set forth, consisting in producing varying power factors in respective components of received impulses and energizing by such components apparatus responsive only at substantially given power factors of such components, substantially as set forth.

52. The method herein set forth, consisting in varying the power factors of components of the energy of received impulses and energizing by such components apparatus operative only at substantially a given difference between the power factors of such components, substantially as set forth.

53. The method herein set forth consisting in producing two energy components from received impulses, opposing one against the other, and by means related to a given fre-

quency producing an operative difference in such energy components only when such impulses have substantially a given frequency, substantially as set forth.

54. The method herein set forth consisting in producing more than one energy component from received impulses, varying the power factor of such components respectively and independently, and energizing by such components apparatus operative only at substantially a given frequency of such impulses, substantially as set forth.

55. The method herein set forth consisting in modifying by separate reactances the phase of energy components of received electrical impulses and energizing by such phase-modified energy components apparatus operative only at substantially a given amount of phase modification in such components, substantially as set forth.

56. The method herein set forth consisting in energizing biphasic apparatus operative only at substantially a given phase difference by separate energy components of received electrical impulses and by means related to a given frequency causing a phase difference between such energy components, substantially as set forth.

57. The method herein set forth consisting in causing phase-differing components from received impulses and energizing thereby responsive apparatus operative only at substantially a given phase difference between such components, substantially as set forth.

Patent No. 755,586

It is hereby certified that in Letters Patent No. 755,586, granted March 22, 1904, upon the application of Daniel Watts Troy, of New York, N. Y., for an improvement in "Methods of Selecting Electrical Impulses," errors appear in the printed specification requiring correction, as follows: In lines 100, 102, 105, 108, 113, page 2, the reference letter and numeral "N²" should read $N/2$; and that the said Letters Patent should be read with these corrections therein that the same may conform to the record of the case in the Patent Office.

Signed and sealed this 24th day of May, A. D., 1904.

[SEAL.]

E. B. MOORE,
Acting Commissioner of Patents.

operative only at substantially a given modification of such components, substantially as set forth.

48. The method herein set forth, consisting in causing phase differences between components of received impulses and energizing by such phase-differing components apparatus responsive only at substantially a given phase difference between such components, substantially as set forth.

49. The method herein set forth, consisting in causing, by means related to a given frequency, a phase difference between components of received impulses, and energizing by such phase-differing components apparatus responsive only at substantially such given frequency, substantially as set forth.

50. The method herein set forth, consisting in causing, by means related to a given frequency, modifications in the power factor of divided components of received impulses, and energizing by such divided components apparatus operative only at substantially such given frequency, substantially as set forth.

51. The method herein set forth, consisting in producing varying power factors in respective components of received impulses and energizing by such components apparatus responsive only at substantially given power factors of such components, substantially as set forth.

52. The method herein set forth, consisting in varying the power factors of components of the energy of received impulses and energizing by such components apparatus operative only at substantially a given difference between the power factors of such components, substantially as set forth.

53. The method herein set forth consisting in producing two energy components from received impulses, opposing one against the other, and by means related to a given fre-

quency producing an operative difference in such energy components only when such impulses have substantially a given frequency, substantially as set forth.

54. The method herein set forth consisting in producing more than one energy component from received impulses, varying the power factor of such components respectively and independently, and energizing by such components apparatus operative only at substantially a given frequency of such impulses, substantially as set forth.

55. The method herein set forth consisting in modifying by separate reactances the phase of energy components of received electrical impulses and energizing by such phase-modified energy components apparatus operative only at substantially a given amount of phase modification in such components, substantially as set forth.

56. The method herein set forth consisting in energizing biphasic apparatus operative only at substantially a given phase difference by separate energy components of received electrical impulses and by means related to a given frequency causing a phase difference between such energy components, substantially as set forth.

57. The method herein set forth consisting in causing phase-differing components from received impulses and energizing thereby responsive apparatus operative only at substantially a given phase difference between such components, substantially as set forth.

In witness whereof I have hereunto signed my name at New York, N. Y., the 8th day of July, 1903.

Patent No. 755,586

It is hereby certified that in Letters Patent No. 755,586, granted March 22, 1904, upon the application of Daniel Watts Troy, of New York, N. Y., for an improvement in "Methods of Selecting Electrical Impulses," errors appear in the printed specification requiring correction, as follows: In lines 100, 102, 105, 108, 113, page 2, the reference letter and numeral "N²" should read $N/2$; and that the said Letters Patent should be read with these corrections therein that the same may conform to the record of the case in the Patent Office.

Signed and sealed this 24th day of May, A. D., 1904.

[SEAL.]

E. B. MOORE,
Acting Commissioner of Patents.

Patent No. 755,586.
